CLAIM

The ornamental design for a cordless handset telephone or similar article, as shown and described.

DESCRIPTION

FIG. 1 is a right side elevational view of a cordless handset telephone or similar article, the side opposite being a mirror image thereof, showing our new design;

FIG. 2 is a rear elevational view thereof;

FIG. 3 is a top plan view thereof;

FIG. 4 is a front elevational view thereof;

FIG. 5 is a bottom plan view thereof.

FIG. 1

FIG. 2

FIG. 3

FIG. 4

FIG. 5
